UNITED STATES PATENT OFFICE.

LEVI C. BOYINGTON, OF CHICAGO, ILLINOIS.

SPRING BED-BOTTOM.

SPECIFICATION forming part of Letters Patent No. 241,916, dated May 24, 1881.

Application filed February 5, 1880.

To all whom it may concern:

Be it known that I, LEVI C. BOYINGTON, of Chicago, in the county of Cook and State of Illinois, have invented certain new and useful 5 Improvements in Spring Bed-Bottoms; and I hereby declare the following to be a full, clear, and exact description thereof, which will enable others skilled in the art to which my invention appertains to make and use the same, 10 reference being had to the accompanying drawings, forming a part hereof, and in which—

Figure 1 represents an end view, and Fig. 2 a side view, of a bed-bottom embodying my invention.

15 Like letters of reference indicate like parts. My invention relates to that class of bed-bottoms known as "spring bed-bottoms;" and it consists in the combination and construction of the several parts, as hereinafter described 20 and claimed.

Bed-bottoms have heretofore been made consisting of a woven-wire fabric stretched from end to end and attached to the end rails of the frame, but they are objectionable, for the reason 25 that the fabric has to be stretched to so great a degree from end to end, for the purpose of obtaining an even and level support for the occupant, as to almost, if not entirely, destroy the elasticity or recoil of the fabric, and so that 30 after it has been in use for a short time it will become depressed or sag in the center, the point or place where support is most needed, and thereby become uncomfortable.

In another instance a bed-bottom has been 35 made by supporting a woven-wire mattress on a series of spiral springs interposed between said mattress and slats arranged transversely between the sides of the bed-bottom framing, but in such instance the woven mattress has 40 been supported along its sides by iron rods extending from end to end of the bed-bottom framing, while the ends of the mattress are connected with and supported by transverse rods supported by the aforesaid side rods. 45 The side rods, which connect with and support the sides of the mattress, owing to their length and unsupported centers, soon become bent downward and inward, due to strain exerted upon them by weight of a person sitting 50 upon or occupying the bed, and therefore the mattress loses its original or normal and

much-desired form, being unable to resume its normal original shape by pressure of the rod if bent. The end rods, which connect with and support the mattress, are liable to the 55 same objections. These objections are obviated altogether by my invention, because I permanently and directly connect the woven-wire mattress, in a stretched condition, to the end rails of the bed-bottom framing, leaving 60 the sides of the mattress free of rigid central supports; therefore, when the sides of the mattress are forced or bent downward or inward by weight of a person exerted thereon said sides will, by their resiliency, instantly resume 65 their original normal stretched condition.

In the drawings, A represents the side rails and B the end rails, of the bed-bottom frame, and which may be made of any known form and material, and united together in any known 70 manner that will be sufficiently firm and strong for the purpose intended.

C represents the mattress or bed-bottom proper, made of woven wire in the usual manner, the ends only of which are attached to the 75 end rails by means of nails or staples, or in any other suitable manner. The woven-wire mattress C, before being permanently attached to both ends of the rails B, is slightly stretched from end to end, but not to such extent as to 80 destroy the elasticity or recoil of the fabric, but so that the tension thereof shall act as a spring-support. The central portion of the mattress C is raised above the plane of the end rails, B, so as to form a crowning surface, as 85 shown, by the upward thrust of a series of spirally-coiled springs, E, which are arranged below the mattress C, and which are supported by a series of slats, D, which are attached to the side rails, B, in the usual manner. The 90 springs E support the mattress C at the point where the greatest support is needed, and the mattress C tends at the same time to hold the springs and prevent them from moving out of their proper position, and so that the spring- 95 support of both the mattress C and springs E is evenly distributed in that portion of the bed-bottom where most needed, and consequently makes a more durable bed-bottom than when the fabric or springs are employed separately. 100

Having thus described my invention, what

I claim as new, and desire to secure by Letters Patent, is—

In combination with the end and side rails of a bed-bottom and spiral springs supported on slats connected therewith, a stretched woven-wire mattress connected permanently and directly with the end rails, said stretched

mattress having no other supports than the end rails and spiral springs, all substantially as and for the purpose specified.

LEVI C. BOYINGTON.
